UNITED STATES PATENT OFFICE

2,101,966

MANUFACTURE OF BOXES

Alexander Gerard Anton van den Bogaert, Surbiton, England, assignor to No-Nail Cases Proprietary Limited, London, England, a limited liability company of Victoria, Australia

Application June 27, 1935, Serial No. 28,755
In Great Britain July 3, 1934

1 Claim. (Cl. 229—23)

This invention relates to improvements in the manufacture of boxes of the type in which there is first formed, in the flat, a blank which is capable of being folded up into bottom, two opposite sides, and possibly the top of the box, and to which, when folded up, two end pieces are added to complete the box.

In the formation of blanks for boxes of this type it has been customary to employ three or 10 four rectangular pieces of 3-ply wood or other suitable material, for forming the bottom, two opposite sides and possibly the top of the box, and to unite these separate pieces into a folding blank by means of strips of metal of angle section 15 affixed on opposite sides of the blank. Such a box, and a suitable strip for the production thereof are described for example in the specification of Letters Patent of the United States No. 1,960,638.

According to the present invention a foldable blank for the production of boxes of this type is produced by taking a single sheet of foldable material, such as cardboard or millboard, and creasing it transversely into three or four parts corresponding to the bottom, opposite sides and possibly the top of the box, and affixing to opposite sides (usually the long sides) of this blank strips of metal of angle section similar for example to those described in the above-numbered 30 United States patent specification. The flanges of the metal strips are provided with notches at points which register with the transverse creases in the cardboard blank, so that the whole can be folded up, when required, into box form.

The strips are affixed to the blank with a space 35 left between the flanges of the strips and the edges of the blank, in the manner also described in the above-numbered United States patent specification, so that grooves or channels are provided into 40 which the end portions of the box, for example rectangles of 3-ply may be inserted.

The present invention is illustrated in the accompanying drawing, in which—

Fig. 1 shows the box blank in the flat,

Fig. 2 shows the blank bent up to box form, with one end piece partly inserted,

Fig. 3 shows the box completed and closed,

Fig. 4 illustrates a detail on an enlarged scale, and

Fig. 5 illustrates a further modification of the invention.

A rectangular sheet A of millboard is creased transversely at B, B, so that the sheet can readily be folded or bent up to form the bottom A², opposite sides A¹, A³ and top A⁴ of a box, as shown

in Fig. 2. Along the edges of the sheet are fixed toothed strips C, C of metal, having flanges C¹, C¹ spaced from the edges of the sheet A, to form in known manner a groove at each side of the box blank for the reception, when the blank is folded, of the end pieces, of which one, partially inserted, is indicated at D. The end pieces may with advantage be made of 3-ply wood. The flanges of the metal strips are notched in known manner opposite to the creases B, B, to permit of the strips being bent; and the strips are attached to the sheet A by means of the teeth of the strip which are passed through the sheet A and are bent over.

The end pieces D are, as shown, provided with 15 lugs D¹, D¹ which engage behind the edges of the upright sides A¹, A³ in known manner to hold the sides in position when the box is being filled. To enable the lugs D¹ to pass behind the rear side member A³ of the box, notches B' are made 20 in the edges of the cardboard sheet A, at the ends of the crease B between the parts A³ and A⁴. These notches B' uncover the body portion C of the metal strips at these points.

Preferably the blank is formed with a fifth 25 portion A⁵, as shown in Fig. 1, to facilitate closure, the part A⁵ being folded down outside the part A¹, when the lid is closed, and secured in position by means of adhesive paper for example, as indicated in dotted lines at E in Fig. 3, or by glueing. 30

If it preferred to have a box with the lid 35 separate from the remainder, the blank will consists of the parts A¹ A² and A³ only; and the lid part A⁴ may be furnished with a flap A⁵ at each side for attachment as before.

In order to give additional depth to the grooves at the side of the blank for the reception of the end pieces of the box, strips F of millboard or other material may be laid along the edges of each portion A¹, A², etc., of the blank (see Fig. 4) 40 and fixed thereto by the teeth of the metal strips. The strips F may be temporarily assembled upon the blanks before the metal strips are attached thereto, e. g., by wire stapling, or by an adhesive.

The additional depth of the grooves hereby provided, particularly where relatively thin material is used for the blank A, facilitates the correct insertion of the end pieces into their places, and also offers additional support for the end pieces for resisting pressure from the outside. 50

If desired the sheet A may have the flanges of the strips C, C attached to it with the flanges C¹, C¹ close up to the edges of the sheet, and the grooves for the end pieces D may be formed as shown in Fig. 5 by attaching to the sheet, strips 55

F of millboard or the like inset from the edge of the sheet. The blank A is here in effect provided with a shoulder along its edges.

A great advantage afforded by the present invention as compared with the manufacture of boxes with the blank made up of separate portions for bottom, sides, etc., is that comparatively cheap material, e. g. millboard may be used in place of the 3-ply or other wood panels hitherto used without, however, sacrificing more than a small proportion of the strength of the box. Although the boxes made by the known process, with separate pieces constituting bottom, sides and top of the box, are surprisingly strong for their weight, nevertheless they may, under great stresses, open or gape along the lines where adjoining pieces meet, whereas with the box blank according to the present invention the portions of the blank forming the sides, bottom and top are all united and any tendency to gape at the corners under end pressure is resisted. The preferred method of closure above described joins the ends of the folded blank to one another, thus completing the strengthening of the box.

Although I have described and illustrated a metal strip which is attached to the foldable blank by means of a number of teeth formed in the strip itself, my invention is not confined to the use of metal strips of this kind. With a blank

of millboard the metal strip may be affixed by means of rivets for example.

I claim:

A box comprising end members, a body member in a continuous sheet creased transversely so that it will readily fold into a bottom, two sides and a top, continuous metallic reenforcing strips each having a body portion provided with teeth and a flat border flange extending at right angles to the body portion of said strips and on the same side thereof as the teeth, said strips being fixed to the outer surface of the longitudinal edges of said body member with their flanges opposite and spaced from such edges, the teeth of said metal reenforcing strips extending through the longitudinal edge portions of said body member, the edges of said body member cooperating with the inner surface of said flanges of the metal reenforcing strips to form continuous channels to receive the respective end members, the said body member being slotted at each edge on the line where the top portion of the body member adjoins the remainder of the body member, and said end members being provided with turned lugs adapted to engage behind the edges of the side portions of said body member when the said end members are inserted in said continuous channels.

ALEXANDER GERARD ANTON

VAN DEN BOGAERT.
